United States Patent Office

Des. 201,708
Patented July 20, 1965

201,708

HYGROMETER

Hansrudolf Stoop, Baar, Zug, Switzerland, assignor to
Defensor Aktiengesellschaft, Zurich, Switzerland, a corporation of Switzerland

Filed Dec. 2, 1963, Ser. No. 77,630

Claims priority, application Switzerland June 7, 1963

Term of patent 14 years

(Cl. D52—7)

Fig. 1.

Fig. 2.

FIG. 1 is a view in perspective as seen from the front of a hygrometer, showing my new design;

FIG. 2 is a view in perspective as seen from the rear thereof;

FIG. 3 is a front elevational view thereof;

FIG. 4 is a side elevational view thereof; and

FIG. 5 is a bottom plan view thereof.

The undisclosed side of the hygrometer is substantially the same in appearance as the side shown.

I claim:

The ornamental design for a hygrometer, as shown and described.
